KEY BOLT

Filed Aug. 1, 1927

³ Inventor: Frank B. Bell
Munday, Clarke & Carpenter Atty.

UNITED STATES PATENT OFFICE

FRANK B. BELL, OF PITTSBURGH, PENNSYLVANIA

KEY BOLT

Application filed August 1, 1927. Serial No. 209,724.

The invention relates in general to key-bolts and has particular reference to a key-bolt construction in which the key is adapted to lock itself in place on being assembled in position in the bolt.

The principal object of the invention is the provision of a novel key-bolt construction comprising a slotted bolt, a key arrangeable through said slotted bolt, and means for automatically deforming the key to lock it in place as it is arranged in engaged position.

A further object of the invention is the provision of a key-bolt construction comprising a bolt having a slot therein and a key adapted for engagement through the slot, and a gib key also arrangeable in the slot and adapted to deform the key as it is arranged in engaged position in the slot to provide a means for locking the same in engaged position.

Still another important object of the invention is the provision of a key bolt construction having a self-locking key.

Numerous other objects of the invention will be apparent as it is better understood from the following description, which, taken in connection with the accompanying drawings, discloses a preferred embodiment thereof.

Referring to the drawing:

Fig. 1 is a perspective view of a key-bolt construction embodying my invention.

Fig. 2 is a cross-section taken substantially along line 2—2 of Fig. 1;

Fig. 3 is an enlarged perspective view of a gib key providing the automatic feature of the key-bolt construction of my invention; and

Fig. 4 is a cross-section of parts taken substantially along line 4—4 of Fig. 1 and illustrating the locking operation of the gib key.

To illustrate my invention I have shown on the drawings a bolt having a shank 11 and a head 12. A rectangular diametral slot 13 having upper and lower parallel edges 14 is formed through the shank of the bolt. A key 15, formed of a strip of iron or other convenient key material and having a thickness sufficient to allow engagement of

the key between opposite lateral sides of the slot 13, is provided for engagement in the inner portion of the slot, and a gib key 16, of substantially the same thickness, is adapted for engagement through the outer portion of the slot.

The gib key comprises a rectangular body 17, the thickness of which is such as to allow its easy insertion through the slot 13, the key having a sliding fit between the lateral sides of the slot. At one end of the key a shoulder 18 is formed and protrudes from an edge 19 of the body. At the opposite end of the key a second shoulder 21 is formed which protrudes from the opposite edge 22. The shoulder 21, at its lower edge 23, lies in the plane of the body 17, but the upper portions of the shoulder 21 are offset from the plane along lines of bend 24, the plane of the shoulder portions being disposed at an angle with the plane of the body 17, and the upper edge 25 of the shoulder being displaced from the plane of the body a distance equal to the thickness of the body.

The key 15 comprises a strip of suitable material and is substantially rectangular in cross section having parallel upper and lower edges 31 and 32. A slot or kerf 33 is formed in the body of the key parallel with the sides 31 and 32 and extends from one end 75 of the key to adjacent the other, terminating at an enlargement 34 and dividing the key into two prong portions 35 and 36, the latter having a width equal to the width of the shoulder portion 18 of the gib key. The 80 key 15 and the gib key 16 are arranged to be adjacently mounted in the slot, the sum of the width of both keys being substantially equal to the total width of the slot 13 between upper and lower sides.

The gib key is first arranged in the outer portion of the slot 13, the edge 19 having engagement with the outer side 14 of the slot, and the shoulder 18 engaging the side of the bolt immediately adjacent the slot. 95 The main strip 17 of the gib key extends through the slot and the shoulder 21 is arranged adjacent the opposite side of the bolt, the offset upper edge of the key engaging the surface of the bolt adjacent the lateral 100

edge of the slot opening. The gib key is assembled in the slot by inserting the end having the shoulder 18 through the slot from one side of the bolt and arranging the key in position in the outer portion of the slot. The key 15 is then inserted into the inner slot portion from the opposite side of the bolt, that is to say, the side of the bolt from which the head of the gib key protrudes. The key 15 is assembled through the slot 13, the edge 31 of the key having sliding engagement with the inner slot wall 14 and the other edge 32 of the key sliding upon the adjacent edge 22 of the gib key. As the key is driven through the slot, the end 37 of the prong portion of the key engages the sloping shoulder 21 of the gib key and is deformed thereby gradually assuming the final position illustrated in Fig. 2 of the drawings, as the key is forced into engaged position in the bolt. The key 14 is automatically deformed as it is forced into position in the bolt and being so positioned cannot be withdrawn from the slot without laboriously unbending the curled-up portion 37. The arrangement thus provides a self-locking key-bolt construction, the parts of which are simple and inexpensive and yet sufficiently rugged to give adequate key-bolt service.

It is thought that the invention and many of its attendant advantages will be understood from the foregoing description, and it will be apparent that many changes may be made in the form, construction and arrangement of the parts without departing from the spirit and scope of the invention or sacrificing all of its material advantages, the form hereinbefore described being merely a preferred embodiment thereof.

I claim:

The combination of a bolt having a slot formed therethrough, a gib key mounted in said slot and having shoulders engaging the face of the bolt shank on opposite sides, and a locking key arranged through the remainder of the slot and having a part deformed by a said shoulder of the gib key, said deformation causing the locking key to engage the face of the bolt shank to lock against retraction in one direction, the other shoulder of the gib key preventing dislodgment thereof in the opposite direction.

FRANK B. BELL.
